CLAIM

The ornamental design for a package, as shown and described.

DESCRIPTION

FIG. 1 is a perspective view of a package wherein the oblique surface shading is intended to show that whole portion of the article including inner portion is transparent;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a cross-sectional view taken along line **8-8** of FIG. 2 and wherein all but the sectioned portions are omitted;

FIG. 9 is a referential front perspective view thereof with its front cover opened to show the surface configuration of the claimed portion without transparency for configuration clarification purposes; and,

FIG. 10 is a referential perspective view to show the surface configuration of the solid line portion as if it were opaque for configuration clarification purposes.

The broken lines are included for the purpose of illustrating the visible, interior portions of the package that for no part of the claimed design.
